UNITED STATES PATENT OFFICE.

WILLIAM H. PFAHLER, OF PHILADELPHIA, PENNSYLVANIA, ASSIGNOR TO
THE ABRAM COX STOVE COMPANY, OF SAME PLACE.

FLUE STRUCTURE OF COOKING RANGES OR STOVES.

SPECIFICATION forming part of Letters Patent No. 430,085, dated June 10, 1890.

Application filed June 25, 1888. Serial No. 278,087. (No model.)

To all whom it may concern:

Be it known that I, WILLIAM H. PFAHLER, a citizen of the United States, and a resident of Philadelphia, Pennsylvania, have invented 55
certain Improvements in Flue Structures of Cooking Ranges or Stoves, of which the following is a specification.

One object of my invention is to provide for the ready removal and insertion of the 10 dividing-strip in the flue of a stove or range, a further object being to construct a built-in range with side flues for the oven or for each oven, and a lower flue or flues which can be readily cleaned from the front of the range.

It has been the usual custom, in constructing what are termed "built-in" ranges, to form the oven-flues in the rear, so that the 15 partition-plate in the flue under the oven may run from front to rear in order to permit the removal of the dust and soot in the flues from the dust-opening in the front of the range.

In what are termed "portable" ranges—that is, ranges that are not built in permanent brick-work—it has been customary and 20 it is preferable to have the oven-flues situated at the side of the oven, and to provide two openings, one on each side of the partition-plate of the lower flue, for the purpose of 25 cleaning the flue on each side of the said plate; but it has hitherto been considered impracticable to construct a built-in range on this principle, as the brick-work comes within a few inches of the front of the range, and no 30 opportunity is afforded for side openings for permitting access to the lower flue. I overcome this difficulty in the manner which I 35 will now proceed to describe, reference being had to the accompanying drawings, in which—

Figure 1 is a view of a double oven-range 40 with a portion of the same broken away to illustrate my invention. Fig. 2 is a section on the line 1 2, Fig. 3. Fig. 3 is a section on the line 3 4, Fig. 2; and Fig. 4 is a perspective view of the removable partition-plate.

Referring to the drawings, A represents the 45 brick-work of the range; B, the top plate; D, the front plate; E, the fire-pot door; F, the ash-pit door, and G G the ovens, provided with suitable doors G', only one of which is 50 shown.

The descending and ascending flues a a'

of the range are situated at the outer sides of the ovens, and the flues x x' beneath the bottom g of the oven are separated by a transverse partition-plate I, the products of combustion passing over each oven, as shown by the arrows in Fig. 1, down the flue a, through the flue x, around the partition I, through the flue x', and up the flue a'. The cleaning-opening h in the front plate D of the range is provided with a suitable door h', as usual, and communicates directly with the flue x on the front side of the partition I. It will be seen, therefore, that the flue x can be readily cleaned by a scraper and brush inserted through the opening h; but it would be impossible to clean the rear flue x' without first removing the partition-plate I. I therefore provide for removing and replacing this plate in the following manner: In the bottom g of the oven G, 70 I form a slot e, preferably tapered, as shown in Fig. 3, this slot being of about the same length as the partition-plate I, which has a tapered rib i, adapted to snugly fit in the tapered slot e, as shown in Fig. 3, so as to prevent the escape of gas into the oven G. The plate I has an extension I', which joins the partition-plate f, dividing the up and down flues a a'.

When it is required to clean the rear flue 80 x', the rib i of the partition-plate I is raised by any suitable instrument and the plate withdrawn into the oven, as shown by dotted lines in Fig. 2. A scraper is then inserted through the opening h and the dirt and soot 85 removed from both flues x and x', after which the partition-plate I is replaced.

It will be understood that the draft of the chimney will, under ordinary circumstances, prevent the gases or products of combustion 90 from entering the ovens, the tendency being to draw air from the ovens, rather than to allow products of combustion to enter the same; but practical tests have shown that such a neat fit of the rib i is possible that 95 there is no communication whatever between the oven and the flues.

It will be evident that although I have described and illustrated the detachable flue-strip as applied to the bottom flue of the 100 range, it is equally adapted for application to side flues or back flues, and it may in

many cases be used in portable stoves or ranges, although especially designed for such as are set in permanent brick-work.

Having thus described my invention, I claim and desire to secure by Letters Patent—

1. The combination, in a cooking stove or range, of the oven, the side and bottom flues, with a front plate having a cleaning-opening, with an opening in the bottom plate of the oven, with a partition-plate for the bottom flue, having an extension I' to form a continuation of the partition of the side flues, the rib *i* on the partition-plate adapted to close the opening in the bottom plate of the oven, substantially as described.

2. The combination, in a cooking stove or range, of the front plate having a cleaning-

opening directly under the oven-opening, the oven having a bottom plate *g*, slotted, substantially as described, with a flue-dividing plate forming a continuation of the dividing-plate in the side flues, said plate being in such proportion as to be removed from the flue through the slot in the bottom plate of the oven, with a rib on the said plate tapered to fit the tapered slot in the bottom plate of the oven, substantially as described.

In testimony whereof I have signed my name to this specification in the presence of two subscribing witnesses.

WM. H. PFAHLER.
